(57) **CLAIM**

The ornamental design for a christmas light arch, as shown and described.

DESCRIPTION

FIG. 1 is a front, right and top perspective view of a christmas light arch, showing my new design;

FIG. 2 is a rear, left and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and

FIG. 9 is an exploded view of FIG. 1;

FIG. 10 is an enlarged view of portion 10 in FIG. 1; and, FIG. 11 is an enlarged view of portion 11 in FIG. 1.

The broken away symbols in the drawings indicate that any portion of the article between the break lines forms no part of the claimed design.

The dot-dash broken lines depict the boundaries of the enlargements that form no part of the claimed design.
